UNITED STATES PATENT OFFICE.

JACOB SODERBERG, OF PITTSBURGH, PENNSYLVANIA, ASSIGNOR TO PITTSBURGH PLATE GLASS COMPANY, A CORPORATION OF PENNSYLVANIA.

HEADLIGHT GLASS OR LENS.

Application filed February 8, 1921. Serial No. 443,361.

To all whom it may concern:

Be it known that I, JACOB SODERBERG, a citizen of the United States, and a resident of Pittsburgh, in the county of Allegheny and State of Pennsylvania, have made a new and useful invention in Improvements in Headlight Glasses or Lenses, of which the following is a specification.

The invention relates to cover or headlight glasses or lenses of the type shown in my copending application Serial No. 443,362, of even date herewith, being particularly designed for automobile lamps. The present lens constitutes a modification of that shown in said application and differs therefrom in that the refracting prisms are in part placed upon one side of the glass and in part upon the other side, instead of having all of the refracting elements on the one side. The principle or theory of light distribution upon which the two lenses are constructed is similar and the result secured substantially the same. The annular prisms on the one side tend to spread or bend the parallel rays from the reflector away from the axis thereof to give the necessary or desired side lighting, while the horizontal prisms on the other side bend all of the rays downwardly, so that any upward glare is avoided. One embodiment of the invention is illustrated in the accompanying drawings, wherein:

Figure 1 is a rear elevation of the lens; Fig. 2 is a horizontal section on the line II—II of Fig. 1; and Fig. 3 is a vertical section on the line III—III of Fig. 1.

It will be understood that the lens is designed to be used in the usual way with the parabolic reflector which reflects the light therefrom theoretically in substantially horizontal rays. However, due to the fact that the filament of the lamp employed cannot be concentrated at the focus of the lens and extends forward and backward of such focus, a part of the reflected light is more or less divergent from the axis of the parabola, such divergence being greatest with respect to those rays which are reflected from those portions of the reflector nearest its center. This condition is taken into consideration in the design of the lens, the angles of the horizontal prisms nearest the center of the lens being accentuated to give a greater bending down effect as com-

pared with the prisms adjacent the upper and lower edges of the lens.

The concentric diffusing ridges or prisms on the rear face of the lens are so designed that the light will be spread laterally,—that is in a horizontal plane, to just the amount necessary to give the degree of side lighting required. The horizontal prisms on the front face of the lens are then so designed that the diverging transmitted light is bent downward, so that the greater portion of the light is thrown upon the roadway at the desired distance forward of the lens, the light passing through the extreme upper edge of the lens being bent downwardly so that it is either horizontal or very nearly so, the purpose being to fulfill the requirements of the law for protecting the occupants of approaching vehicles from glare due to upwardly directed beams of light.

Referring now to the drawings, 1 is the edge portion of the lens adapted to be fitted in the rim of the lamp; 2, 3, 4, 5 and 6 are concentric ridges or prisms upon the rear face of the lens, and 7 to 17 are horizontal prisms extending across the front face of the lens. The prisms 2 to 6 are of such angle that the parallel rays from the parabolic reflector passing therethrough are bent outwardly from the axis A of the reflector, the amount of the bending being determined by the amount of side lighting desired. The prisms 7 to 17 bend this diverging light downwardly to the desired extent with respect to the area upon the ground in front of the lens which it is desired to illuminate. The rays passing through the upper portion of the lens must, of course, be bent downwardly more than those passing through the lower portion since the rays from the upper portion of the lens are bent upward by the prisms on the inside of the lens, while those on the lower portion are bent downwardly by such prisms. The angles of these horizontal prisms may be varied in order to secure just the amount of downward bending desired, and it will be understood that the illustration is not by any means exact, the angles of the prisms being greatly exaggerated in order to more clearly illustrate the principles of the construction. The angle of the central transverse prisms 10, 11, 12 and 13 are made greater than would be

called for if the light from the filament of the lamp were concentrated at the focus of the lens as heretofore referred to. The rays reflected from the central portion of the reflector, due to this condition, have a greater degree of divergence than those from the outer portion of the reflector, so that the angles of the central transverse prisms are made relatively heavier than would otherwise be the case. The angles of the other transverse prisms above the axis of the lens are so designed that very little, if any, of the light transmitted passes above a horizontal plane, the objectionable glare which would otherwise occur, being thus avoided.

With respect to the angle of the prisms below the axis of the lens, this is made to suit requirements and given just the desired amount of illumination in the area of roadway ahead of the car to which the lens is applied, the angles of the prisms on the front of the lens and those on the back being carefully designed to avoid dark lines in the area illuminated and a uniform shading off of intensity from the center of the field of illumination to the outer edges thereof. The curved faces on the concentric prisms assist in securing this effect as the light passing therethrough is diffused so that the light from the various concentric zones overlaps and blends. The transverse ridges also tend to break up any tendency to produce the appearance of concentric bands in the field of illumination incident to the use of the concentric prisms.

One great advantage of this lens is that the molds may be machined, there being no requirement for hand chipping such as is the case in the molds used for the formation of lenses in which the prisms are not continuous. Such molds are not only expensive to make because of the hand work required, but are correspondingly hard to re-surface after a certain amount of use. The face of the mold which produces the concentric ridges of the applicant's lens may be machined in a lathe while the plunger which forms the transverse prisms may be machined in a planer or milling machine. When the mold members need to be refinished, this can be quickly and cheaply done following the method by which the mold members were originally machined. Because of this possibility of machining the mold members may also be made of exceedingly hard, durable material, such as nichrome or stellite. This material may be machined or ground but could not possibly be used in molds which require hand work, so that if desired, the applicant may produce his molds from material which may be used almost indefinitely before requiring re-surfacing and which will give a better surface on the glass than cast iron or other molds of relatively soft material.

The prism arrangement of the lens is capable of considerable variation in the arrangement and angles of the prisms without departing from the broad idea involved of providing the circumferential or annular prisms on one side for bending the rays outwardly from the axis of the lens and of providing the transverse prisms on the other side for bending the rays downwardly. The angles of both sets of prisms may be modified to suit conditions or the requirements of the law as it may exist in various States. This is particularly true of the prisms on the front side of the lens. It is necessary and most desirable that the light passing through the upper half of the lens be bent downwardly so that the uppermost rays are horizontal or approximately so in order to avoid glare and avoid wasting a portion of the illumination, but this is not so essential in the lower portion of the lens in which the light is for the most part bent downwardly by the annular prisms on the rear face of the lens. The degree of additional bending downward of the rays by the horizontal prisms is more or less a matter of discretion, such rays being bent down little or much, depending upon the lighting desired. Similarly as to the variation in angle of the prisms in the upper half of the lens, the angle preferably increasing upward from the center as illustrated, for the reasons heretofore stated, but this is not necessarily the case and the degree of angle may be considerably changed. It is, however, quite important that the light transmitted through the lower part should be bent downwardly somewhat in order to give the proper illumination immediately in front of the car. Also that that portion of the light transmitted just below the center of the lens should be bent down more than that transmitted further down, as the lateral divergence of such light is so great as to be of little use for side lighting when bent down sharply; however, this light is brought close enough to the car and to the center of the field of illumination to be of value.

What I claim is:

1. In combination in a headlight lens or cover glass for use with a parabolic reflector, a plate of glass provided on one side with a series of complete annular prisms substantially symmetrical throughout their circumference adapted to bend substantially all of the parallel rays from the reflector away from the axis thereof and provided on the other side with a plurality of transversely extending prisms adapted to bend the rays downwardly, the angles of those transverse prisms nearest the center being greater than those above and below.
2. In combination in a headlight lens or cover glass for use with a parabolic reflector, a plate of glass provided on one side with a

series of complete annular prisms substantially symmetrical throughout their circumference adapted to bend substantially all of the parallel rays from the reflector away from the axis thereof and provided on the other side with a plurality of transversely extending prisms adapted to bend the rays

downwardly, the angles of those transverse prisms nearest the center being greater than those below the center.

10

In testimony whereof, I have hereunto subscribed my name this 2nd day of February, 1921.

JACOB SODERBERG.
